DESIGN FOR A HANDBAG OR SIMILAR ARTICLE

Louis J. Coblenz, New York, N. Y.

Application July 18, 1940, Serial No. 93,764

Term of patent 3½ years

To all whom it may concern:

Be it known that I, Louis J. Coblenz, a citizen of the United States of America, residing in New York, county of New York, and State of New York, have invented a new, original, and ornamental Design for a Handbag or Similar Article, of which the following is a specification, reference being had to the accompanying drawing, forming part thereof.

Fig. 1 is a perspective view of a handbag or similar article showing my new design.

Fig. 2 is a top plan view thereof.

The dominant features of my design reside in the portions shown in full lines.

I claim:

The ornamental design for a handbag or similar article, as shown and described.

LOUIS J. COBLENTZ.
